UNITED STATES PATENT OFFICE.

GHEEN R. ABBOTT, OF BALTIMORE, MARYLAND.

EARTH CARRIER AND DUMPER.

1,087,343.

Specification of Letters Patent.

Patented Feb. 17, 1914.

Application filed March 20, 1913. Serial No. 755,605.

To all whom it may concern:

Be it known that I, GHEEN R. ABBOTT, a citizen of the United States, residing at Baltimore, in the State of Maryland, have invented certain new and useful Improvements in Earth Carriers and Dumpers, of which the following is a specification.

This invention relates to an earth carrier and dumper.

10 The object of the invention is to provide improved means for operating a two-part dumping bottom of a receptacle for earth excavations, so that both parts of the bottom may be opened and closed by moving a bar 15 at one side of the receptacle.

The invention is illustrated in the accompanying drawing, in which,

Figure 1 is a longitudinal side view of the receptacle. Fig. 2 is an end view of the receptacle in which the two-part bottom and the mechanism for operating the same are shown in the closed position. Fig. 3 is also an end view in which the mechanism and bottom parts are shown in the open position.

25 Referring to the drawing the receptacle has two vertical ends, A, which are broader on a horizontal line across the top than at the bottom, and the bottom has a curved lower edge, b; the two sloping sides, C, are 30 connected with said ends, and these parts are open at top and bottom.

The closure for the open bottom consists of two curved plates, d, d¹, of equal width, the two together being of the same width as 35 the curved part, b, and said plates having a length equal to the longitudinal length of the sides, C. When the said two curved parts, d, d¹, have their inner edges in contact with each other along the center line, e, as in Fig. 40 2, said parts constitute a closed bottom for the walls of the receptacle. Each curved plate, d, is stiffened lengthwise by an angle bar, f, extending along its lower surface at the outer edge, and also by a bar, g, along 45 its inner edge. Each curved bottom plate is carried by two swinging hangers, H, H, these two constituting a pair; one of said hangers being at one vertical end, A, and the other hanger at the opposite vertical end.

50 Thus one pair of hangers, H, support one bottom-plate, d, and the other pair of hangers, H¹, support the other bottom plate, d¹. Each hanger is attached by a pivot pin or bolt, i, through its upper part, to a vertical end, A, of the receptacle; these pivots permit the hangers and bottom-plates to

swing from the closed position seen in Fig. 2, to the open position shown in Fig. 3, and vice versa. The improved mechanism to produce this swinging movement will now be 60 described.

A lever, J, is at each of the two ends, A, of the receptacle and said lever, is pivoted intermediate of its ends by a pin or bolt, k, and the lever has vertical movement. An elbow having two jointed arms, l, l¹, is employed and combined at opposite ends of the receptacle with each swinging hanger; one arm, l, of each elbow is attached by a pivot, m, to the receptacle, and the other arm, l¹, is attached by a pivot, n, to a swinging hanger. Referring to Fig. 2, it will be seen the elbow at the left-hand side is extended or straightened out by an upward movement of the center joint, o, of the elbow, and reference to 75 Fig. 3, will show that by a downward movement of the center joint the same elbow is contracted or crooked. The elbow at the right-hand side has the same structure exactly but the parts are differently positioned, 80 with the result that the upward and downward movements of its center-joint, o¹, produces respectively a contraction and an extension which is exactly the reverse action of the first-named elbow. The said lever, J, 85 extends between the two elbows, and the lever pivot, k, is also between the two elbows; a link, p, is jointed to the lever, J, at one side of its pivot, k, and extends downward from the lever and connects with the center-joint, o, of the left-hand elbow. Another link, q, is jointed to the said lever at the opposite side of the pivot, k, and extends upward from the lever and connects with the center-joint, o¹, of the right-hand elbow. 90 The result of this arrangement and combination of parts is, that when the longer and free end of the lever is raised, as in Fig. 2, the two-part bottom, d, d¹, is closed; but when the long end of the lever is lowered, as 95 in Fig. 3, the said bottom is opened.

As shown in Fig. 1, the two levers, J,—one at each end—are connected by a rod or bar, r, that extends along the side of the receptacle, by moving this rod both levers will 105 be actuated. At one or both ends of the receptacle is a flanged plate, s, having holes t; when the levers, J, are raised a pin, u, may be inserted in one of the said holes, t, and said pin will take below the lever and 110 serve to keep the levers in their raised position and prevent the bottom plates, d, d¹,

from opening. When it is desired to dump the load of earth contained in the receptacle, it is only necessary to lower the two levers, J, whereupon the parts assume the position seen in Fig. 3.

5 The receptacle shown may be mounted on wheels to run as a car would in a tunnel or mine; or the receptacle may be lifted bodily by a chain and hooks which latter may engage in holes, v, in the ends of the receptacle; the lifting chain referred to might be operated by a derrick or crane.

Having thus described my invention what I claim and desire to secure by Letters Patent is:—

1. An earth carrier and dumper, consisting of a receptacle having the two ends, sloping sides and open bottom; two plates which together close said open bottom, and 10 each plate carried by two hangers—one at each end of said receptacle—each hanger being attached to the receptacle by a pivot whereby said hangers and the plate may swing; a lever pivoted to said receptacle; 15 two elbows each having two jointed arms, one arm of one elbow being attached by a pivot to the receptacle and the other arm of the same elbow being attached by a pivot to one of the said hangers, and the other elbow having its two arms similarly attached to the receptacle and to the other hanger; two links both of which are jointed to the said lever and one end of each link being connected to the center-joint of a different elbow and a bar extending along the 20 side of the receptacle from one end to the other and connecting the said two levers, whereby on moving said bar both levers may be actuated.

In testimony whereof I affix my signature 25 in presence of two witnesses.

GHEEN R. ABBOTT.

Witnesses:

CHARLES B. MANN, JR.

link being connected to the center-joint of a different elbow.

35

2. An earth carrier and dumper, consisting of a receptacle having the two ends, sloping sides and open bottom; two plates which together close said open bottom, and each plate carried by two hangers—one at 40 each end of said receptacle—each hanger being attached to the receptacle by a pivot whereby said hangers and the plate may swing; two levers pivoted to said receptacle; two elbows each having two jointed arms, 45 one arm of one elbow being attached by a pivot to the receptacle and the other arm of the same elbow being attached by a pivot to one of the said hangers, and the other elbow having its two arms similarly attached to the receptacle and to the other hanger; two links both of which are jointed to the said lever and one end of each link being connected to the center-joint of a different elbow and a bar extending along the 50 side of the receptacle from one end to the other and connecting the said two levers, whereby on moving said bar both levers may be actuated.
